UNITED STATES PATENT OFFICE.

ESKIL BERGSTROM, OF EVANSTON, ILLINOIS.

DESIGN FOR A CANDLE HOLDER.

Application filed September 9, 1925. Serial No. 14,731. Term of patent 14 years.

To all whom it may concern:

Be it known that I, ESKIL BERGSTROM, a citizen of the United States, residing at Evanston, in the county of Cook and State of Illinois, have invented a new, original, and ornamental Design for Candle Holders, of which the following is a specification, reference being had to the accompanying drawing, forming part thereof.

The figure is a perspective view of a candle holder showing my new design.

I claim:

The ornamental design for a candle holder as shown.

ESKIL BERGSTROM.
